(57) **CLAIM**

The ornamental design for a segmented tie, as shown and described.

DESCRIPTION

FIG. 1 is a front view of a segmented tie showing the present design with a neck strap shown in broken lines.

FIG. 2 is an exploded view of the segmented tie.

FIG. 3 is a front view of the segmented tie.

FIG. 4 is a back view of the segmented tie; and,

FIG. 5 is a side view of the segmented tie.

The broken lines shown are included for the purpose of illustrating portions of the segmented tie that form no part of the claimed design.
